DESIGN FOR A SWEATER

Leon Goldsmith, Brooklyn, N. Y.

Application December 26, 1939, Serial No. 89,141

Term of patent 3½ years

To all whom it may concern:

Be it known that I, Leon Goldsmith, a citizen of the United States and resident of New York city, Borough of Brooklyn, in the county of Kings and State of New York, have invented a new, original, and ornamental Design for a Sweater, of which the following is a specification, reference being had to the accompanying drawing, forming a part thereof, and of which Figure 1 is a front view of a sweater showing my new design, and Fig. 2 is a back view thereof.

I claim:

The ornamental design for a sweater, substantially as shown.

LEON GOLDSMITH.
